Primary Examiner—Louis S. Zarfas*Assistant Examiner*—Monica A. Weingart*Attorney, Agent, or Firm*—Bernhard Kreten**[57] CLAIM**

The ornamental design for a clay pigeon launcher support, as shown and described.

DESCRIPTION

FIG. 1 is a perspective view of a clay pigeon launcher support showing my new design;

FIG. 2 is a front view thereof;

FIG. 3 is a right side view thereof;

FIG. 4 is a top view thereof;

FIG. 5 is a bottom view thereof;

FIG. 6 is a left side view thereof;

FIG. 7 is a back view thereof;

FIG. 8 is a exploded view thereof; and,

FIG. 9 is a perspective view thereof shown in one possible environment.

The broken-line showing of environmental structure in FIG. 9 is for illustrative purposes only and forms no part of the claimed design.
